UNITED STATES PATENT OFFICE.

CHARLES H. BUCHANAN, OF PHILADELPHIA, PENNSYLVANIA.

DESIGN FOR A BELT.

SPECIFICATION forming part of Design No. 16,495, dated February 2, 1886.

Application filed November 2, 1885. Serial No. 181,708. Term of patent 3½ years.

To all whom it may concern:

Be it known that I, CHARLES H. BUCHANAN, a citizen of the United States, residing at Philadelphia, in the county of Philadelphia and State of Pennsylvania, have invented a certain new and useful Design for Belts; and I do hereby declare the following to be a full, clear, and exact description of the invention, reference being had to the accompanying drawing, which forms part of this specification, in which the figure is an elevation illustrating my design.

My design relates to belts which are worn as an article of dress, but which may be used for any purpose to which they are found adaptable.

My design for a belt consists of a series of longitudinal ridges or parallel laps, each having a braided configuration or surface appearance.

My invention consists in a design for a belt having a surface showing braiding or plaiting, such as plaited or braided straw, real or imitation, arranged so as to produce a configuration exhibiting parallel lines or strips which overlap each other, forming ridges or laps. This imparts a fanciful and ornamental ap-

pearance to the belt, which differs in design from a plain belt in two respects—viz., in having a ridged or lapped surface, and in having laps or strands exhibiting the appearance of plaiting or braiding.

Referring to the accompanying drawing, A represents a belt embodying my design, having a series of ridges or laps, B B, each of which has a braided or plaited appearance or surface, said ridges being produced by overlapping strips which extend in parallel lines longitudinally of the belt.

What I claim is—

The design for a belt herein shown and described, the same consisting of a belt provided upon its exterior surface or outer face with an ornamentation representing a series of longitudinal parallel ridges or laps in conventional imitation of braids or plaits, as set forth.

In testimony that I claim the foregoing I have hereunto set my hand this 30th day of October, 1885.

CHAS. H. BUCHANAN.
